UNITED STATES PATENT OFFICE

LAWRENCE S. WILBUR, OF EVANSTON, ILLINOIS, ASSIGNOR TO JOHNS-MANVILLE CORPORATION, A CORPORATION OF NEW YORK

BITUMINOUS CONCRETE FLOORING

Application filed November 25, 1927. Serial No. 235,426.

This invention relates to bituminous concrete flooring, and has for its principal objects to reduce the labor and difficulty of laying and to improve the finished product.

5 Further objects and advantages of the invention will become apparent as the description is read in connection with the accompanying drawings, in which

Fig. 1 is a partial plan view of a railway car illustrating the various stages in the process of laying bituminous concrete flooring; and

Fig. 2 is a sectional view taken on the line 2—2 of Fig. 1.

15 It is to be understood that this specific illustration, and the correspondingly specific description, are used for the purpose of disclosure only, and are not intended to indicate the limits of the invention or its uses.

20 The supporting floor structure of the car is illustrated at 10 as being made of corrugated or channel sheet metal, commonly known in the trade as $\frac{5}{8}$ ths inch chan arch. This is suitably mounted on the frame of the car 25 between the side walls 11 and the end walls 12, and receives the bituminous concrete flooring, generally indicated by 13.

The concrete is made in two layers, which will be termed for convenience a base layer 30 14 (Fig. 2) and a finish layer 15. The following is an illustrative mixture suitable for the base layer.

35 Eighty-five pounds of standard mastic blocks, which may contain 15% of No. 25 penetration flux and 85% of limestone dust and sand to pass 10 to 200 mesh screen; 15 lbs. No. 25 penetration flux; 53 lbs. coke that will pass a 10 mesh screen; and 25 lbs. gravel that will pass 4 to 6 mesh screens.

40 It will be understood, of course, that the character of the materials will be changed to suit particular conditions.

For a lighter mixture the gravel may be eliminated and the flux increased to 22 45 pounds, and the coke increased to 75 pounds.

The finish layer may be made of the same mixture as the base layer, with the exception that instead of the standard mastic blocks maroon or other colored mastic blocks may 50 be used. A very satisfactory block consists

of 17% No. 25 penetration flux; 33% red slate dust passing an 80 mesh screen; and 50% of pulverized red oxide of iron.

Another satisfactory finish mixture consists of 85 lbs. of colored blocks; 85 lbs. of 55 white back sand; and 15 lbs. of No. 25 penetration flux.

A convenient preliminary step to laying the concrete consists in installing longitudinal strips 16 and transverse strips 17 of a height 60 corresponding to the surface of the finished floor. The strip 16 next to the walls 11 may be laid in spaced relation from those walls by blocks 18, and similar blocks may be placed between the strips 17 and end walls 12. 65

In laying the concrete the best results will be obtained by first laying a relatively small portion or area of the base layer and immediately laying thereon a corresponding area of the finish layer, and trowelling or otherwise 70 rolling it to the desired finished surface. For example, in laying car floors on steel floor supports very satisfactory results are obtained by first placing about two buckets or nine square feet of the base layer, striking it off with a straight edge 19 (Fig. 2) notched at the edges 20 to correspond with the thickness of the finish layer, and immediately following the striking off with one bucket or a 75 corresponding area of the finish layer and striking that off with a straight edge 21. Then treat the surface with a float or roller, or both, according to the conditions.

After proceeding in this manner until the two side areas have been laid, the strips may 85 all be removed and the side areas themselves will perform the function of strips while the middle area is laid. The marginal areas may be filled in entirely with the finish material and immediately worked to the finished surface. In ordinary practice car floors are provided with a cove or molding around the margins, in which case an excess of concrete is laid in these areas and the float is applied until substantially all shrinkage has taken 90 place.

In car floors such as illustrated bituminous concrete will be sufficient if it is an inch and a quarter thick over the steel floor supports, and of this one-quarter inch only may be in 100

the finish layer. By laying the finish mixture immediately after laying a small portion of the base mixture the base layer assists in keeping the finish layer at the proper working temperature until it can be brought to a finish. Ordinarily the concrete is laid at a temperature of around 400°, and it works best when somewhere near that temperature. The steel support being a good conductor of heat tends to rapidly reduce the temperature of the concrete, even at ordinary summer temperatures, and this tendency is greatly increased as the atmospheric conditions change toward normal winter temperatures.

15 The hot concrete laid next to layers that have already been placed will cause sufficient fusion of adjacent surfaces to bond them firmly together.

I claim as my invention—

20 1. The process of laying bituminous concrete floors, which includes laying a layer of hot concrete and immediately placing thereon a layer of other hot concrete and working the latter to a finished surface.

25 2. The process of laying bituminous concrete floors, which consists in laying a relatively thick layer of hot concrete and immediately laying thereon a relatively thin layer of hot concrete including a coloring agent, and immediately acting upon the relatively thin layer to produce a finished surface.

30 3. The process of laying bituminous concrete floors, which includes laying a small area of hot concrete of less thickness than the finished floor, and immediately laying thereon a layer of hot surface concrete and immediately rolling the thin layer to a finish.

35 4. The process of laying bituminous concrete floors, which includes laying a layer of hot concrete and immediately placing thereon a layer of other hot concrete while the first layer is at a temperature to prevent the second layer from becoming too cool for finishing and working the latter to a finished surface.

40 5. The process of laying bituminous concrete floors, which includes laying a small area of hot concrete of less thickness than the finished floor, and immediately laying thereon a layer of hot surface concrete while the first layer is at a temperature to prevent the second layer from becoming too cool for finishing and immediately rolling the thin layer to a finish.

45 6. The process of laying bituminous concrete floors, which includes laying a layer of hot concrete and striking off said layer, then immediately applying another layer of concrete on the first layer while it is still hot so that the heat of the first layer will assist in maintaining the temperature of the second layer, and immediately rolling the second layer while hot to a finished surface.

50 In testimony whereof I affix my signature.
LAWRENCE S. WILBUR.
